UNITED STATES PATENT OFFICE.

WILLIAM MILLS AND O. H. BURDETT, OF NEW ATHENS, OHIO.

IMPROVED GAS APPARATUS FOR DOMESTIC USE.

Specification forming part of Letters Patent No. 39,159, dated July 7, 1863.

To all whom it may concern:

Be it known that we, WM. MILLS and O. H. BURDETT, both of New Athens, in the county of Harrison and State of Ohio, have invented a new and Improved Gas Apparatus; and we do hereby declare that the following is a full, clear, and exact description of the same, reference being had to the accompanying drawings, forming a part of this specification, in which—

Figure 1 represents a longitudinal vertical section of our invention. Fig. 2 is a transverse vertical section of the same.

Similar letters of reference in both views indicate corresponding parts.

The object of this invention is to produce a gas apparatus capable of supplying a dwelling-house with gas, and so simple and cheap in its construction and operation that it can readily be put up and operated in every house.

The invention consists in the employment or use of a zigzag or winding concave or perforated tube rising gradually through the purifier in such a manner that the gas is compelled to travel a long distance through the water, and is well washed in a comparatively small quantity.

The invention consists, finally, in the arrangement of a lime-chamber in the movable lid of the purifier having a screen or perforated bottom to support the lime and admit the gas, said lid being connected with the conducting-pipes by a flexible tube, so that it can be removed without breaking the connections.

To enable others skilled in the art to make and use our invention, we will proceed to describe it.

A represents the pipe leading from the retort to the tar-receiver B. Said pipe is so arranged that the upper portion of it on that part emanating from the retort can be readily removed whenever the gas apparatus is not in operation. It extends down near to the bottom of the receiver B, which is partially filled with water and provided with a suitable gate or faucet to draw off the tar which collects at its bottom. At the same time the aqueous vapors contained in the gas are condensed in the receiver and the gas partially purified escapes

through the pipe C to the purifier D. The pipe C extends from the top of the tar-receiver to the bottom of the purifier, as clearly shown in Fig. 1 of the drawings. The purifier is to be nearly filled with water and it is provided with a series of semicircular concaves, E, inclined in opposite directions and provided with openings a, each at or near to its highest end, so that a rising zigzag passage is formed, and the gas which enters through the pipe C under the lower end of the bottom concave, will pass along under this concave to the opening at its highest end, through this opening to the lowest end of the second concave, and so on, until it reaches the opening in the highest end of the top concave. In taking this zigzag course the gas is continually in contact with the water in the purifier, and a comparatively small quantity of water is sufficient to wash the gas.

It is obvious that instead of a zigzag passage a spiral or polygonal rising passage might be formed by the concaves E, and instead of using semicircular concaves, pipes might be used, perforated at the bottom to admit the water from the purifier.

F is the lid of the purifier, which is provided with a screen or perforated bottom, b, covered with lime or other suitable material, capable of absorbing the impurities still remaining in the gas. After having passed through the lime chamber, the gas rises through the pipe c into the gas-holder H, where it is retained for use. This gas-holder is made of some flexible material, and it is so-arranged that it can be loaded with sufficient weight to drive out the gas with the desired pressure. The tube I, which conducts the gas from the purifier to the burners, is made of some flexible material, thus allowing of removing the lid F without breaking the connections, whenever it should be desirable to get to the interior of said purifier for the purpose of cleaning the gas-passage or of recharging it with clean water.

This apparatus is so very simple in its construction that it can readily be put in operation by inexperienced persons, and by the profits derived from the tar collected in the receiver B the cost of the gas is nearly covered.

Having thus fully described our invention, what we claim as new, and desire to secure by Letters Patent, is—

1. The arrangement of the concaves E, or their equivalents, forming a zigzag or winding passage in the interior of the purifier, constructed and operating in the manner and for the purpose substantially as described.

2. The arrangement of a lime-chamber in

the movable lid F of the purifier, in combination with the flexible tube I, constructed and operating as and for the purpose set forth.

WM. MILLS.
O. H. BURDETT.
